UNITED STATES PATENT OFFICE.

RICHARD MORRIS, OF BLACKHEATH, COUNTY OF KENT, ENGLAND.

IMPLEMENT FOR RESIZING, CAPPING, AND UNCAPPING CARTRIDGES.

SPECIFICATION forming part of Letters Patent No. 242,676, dated June 7, 1881.

Application filed December 1, 1880. (No model.) Patented in England June 26, 1880.

To all whom it may concern:

Be it known that I, RICHARD MORRIS, of Blackheath, in the county of Kent, England, have invented an Improved Apparatus for Resizing, Uncapping, and Recapping Cartridge-Cases, (for which I have obtained a patent in Great Britain, No. 2,602, bearing date June 26, 1880,) of which the following is a specification.

When a cartridge has been fired the empty case withdrawn from the fire-arm is somewhat expanded or otherwise forced out of its proper shape, and it has on it the case of the fired percussion-cap.

My invention relates to a simple and portable apparatus, which can be used by troops in the field, for rendering the cases of fired cartridges available for repeated use, this apparatus being arranged so that the cartridge-case is by its use restored to its proper size and shape, has its used cap removed from it, and can be provided with a new cap, so as to be ready for charging, in order to be fired again.

The invention is illustrated in the accompanying drawings, in which Figure 1 is a sectional view of the implement in position for restoring the shell to its true size and shape, and for removing the used cap; Fig. 1^a, a sectional view of the implement in position for recapping the cartridge-shell; and Fig. 2 is a view of the hammer.

The said apparatus is shown in vertical section at Fig. 1, consisting of three parts—an external cylindrical shell, A, bored out internally or bushed to the size and shape of the cartridge-case, a bottom cover, B, fitting the end of A, and an internal mandrel, C, fitting the mouth of the cartridge-case. The mandrel C has on its head a collar working in a recess of the die, so that it cannot be taken out without removing the head of the die, and this collar is hollowed on the top, for a purpose which will presently be explained.

The cartridge-case to be operated on is introduced into the die, and its base is inserted into the hollow of the cover B, which rests on a table or other support. The top of the shell A is then struck with the flat face of a copper or other soft-metal hammer, such as is shown to a small scale at Fig. 2, until it meets the

cover B, the cartridge-case being thus restored to its true size and shape. This being done the hollow head of the mandrel C is struck with the rounded nose D of the hammer, driving the cartridge-case out of the die. The hollowing of the head of the mandrel has the effect of centralizing the blow of D, which, if it is struck at a point not central, or nearly so, might tend to bend the mandrel.

For effecting the removal of the used cap from the cartridge-case the end of the mandrel C is provided with a small punch, E, which, when the mandrel is struck, will force the cap out of the cap-chamber through a hole, b, in the cover B.

Punches of various sizes may be fitted to the mandrel, each being made with a coned butt secured by a coned socket, e, screwed on the end of the mandrel.

The cartridge-case having been thus resized and uncapped the apparatus is turned upside down, as shown at Fig. 3, and the punch removed from the mandrel, an anvil and cap are placed in the cap-chamber, and, the cover B being fitted on, the cap is then driven home in the chamber by means of a capping-stud, B', which is fixed in the cover B, and provided with a head to prevent the cap from being driven in too far. The cover B is then taken off and the prepared cartridge is removed in order to be re-filled. The shell A may be provided with bushes of different sizes to suit various descriptions of cartridges.

Heretofore an implement for loading and capping cartridges has been constructed of a hollow casing and an independent ejector, having at one end a cartridge-dislodging pin, and at the other end a cap-detaching pin; but such, broadly, is not my invention. In my structure the mandrel is entirely inclosed within the exterior shell or casing, and is confined therein by a detachable cap on the shell or casing, and the mandrel is adapted to enter a cartridge-case sustained and supported within one end of the shell or casing to uncaps and resize the cartridge-case.

Having thus described the nature of my invention and in what manner the same is to be performed, I claim—

The mandrel inclosed within the cylindrical bore of the shell, and confined therein by a removable cap on the shell, said mandrel being constructed to be forced into a cartridge-case sustained and supported within one end of the shell for uncapping and resizing said cartridge-case, substantially as and for the purposes described.

In testimony whereof I have hereunto signed my name to this specification in the presence of ^{to} two subscribing witnesses.

RICHARD MORRIS.
